UNITED STATES PATENT OFFICE.

MARTINUS ADRIANUS MEIJER, OF THE HAGUE, NETHERLANDS, AND RICHARD VOM FELD, OF BRUNSWICK, GERMANY.

RECEPTACLE CONTAINING VOLATILE OR INFLAMMABLE LIQUIDS SUCH AS BENZENE
AND OTHER HYDROCARBONS.

Application filed August 15, 1924. Serial No. 732,325.

To all whom it may concern:

Be it known that we, MARTINUS ADRIANUS MEIJER and RICHARD VOM FELD, citizens of Netherlands and Germany, respectively, residing at The Hague, Netherlands, and Brunswick, Germany, respectively, have invented certain new and useful Improvements in Receptacles Containing Volatile or Inflammable Liquids Such as Benzene and 5 Other Hydrocarbons (for which we have applications filed in Germany Jan. 12, 1924, and July 21, 1924), of which the following is a specification.

Our invention relates to improvements in 15 receptacles containing volatile or inflammable liquids such as benzene and other hydrocarbons, and more particularly in safety valves provided in connection with such receptacles for avoiding the loss of gas and 20 inflammation of the liquid, and for compensating the variations of the volume of gas when filling the receptacle or tapping liquid therefrom, and the expansion or contraction caused by variations of temperature. The 25 object of the improvements is to provide a valve system comprising two valves or groups of valves disposed so that one valve or group of valves opens when the pressure within the receptacle exceeds the 30 normal, and that the other valve or group of valves opens when the said pressure is below the normal, the last named valve or group of valves controlling the admission of air or gas. Preferably the receptacle is connected with a receptacle adapted to take up the gas expelled from the storage tank and to supply thereto gas in case of low pressure.

The same reference characters have been 40 used in all the views.

In the drawing,

Fig. 1 is a sectional elevation showing the improved valve,

Fig. 2, is a sectional plan view taken on 45 the line 4—4 of Fig. 1, and

Fig. 3, is a partial sectional elevation of a modification.

The valve casing consists of a tubular portion l^1 and two concentric walls b^1 and b^2 . The chamber provided between the tubular

portion l^1 and the wall b^1 is divided by a horizontal partition i^1 and radial partitions d^1 into compartments k^3 , k^4 , k^5 and k^6 . Valves n and m are disposed in the concentric chambers, and the sectional valve casings are constructed so that all of the valves open in an upward direction, these valves n and m being adapted to open or close passages w^1 and w^2 between the compartments k^3 , k^4 , k^5 and k^6 . The chambers k^3 communicate through passages s with the semi-cylindrical chamber k^7 provided between the left hand part of the walls b^1 and b^2 , which chamber communicates through a tubular part v with the air or with a supply of a suitable gas. The chambers k^6 communicate through an opening r with the semi-cylindrical chamber k^8 provided between the right hand parts of the said walls b^1 and b^2 , which chamber communicates either 60 through an opening t with the outer air, as shown in Fig. 1, or through a tubular part u with a receptacle for storing the gas expelled from the receptacle g , as is shown in Fig. 3. The chambers k^4 and k^5 communicate with the tubular member l^1 through 65 openings q and p .

The operation of the apparatus is as follows: When the pressure within the receptacle g exceeds the normal, gas escapes 80 through the tubular member l^1 , the opening p , the chamber k^5 , the opening w^2 , the chamber k^6 , the opening r , the chamber k^8 and the opening t or the tubular member u into the atmosphere or a storage receptacle. 85 If the pressure is below the normal, gas is drawn in through the tubular part v , the chamber k^7 , the openings s , the chamber k^3 , the opening w^1 , the chamber k^4 , the opening q and the tubular member l^1 into the receptacle g . Under both conditions the valves m or n are raised from their seats. 90

We claim:

In a valve construction of the class specified, the combination with a container for 95 highly volatile and combustible liquids, of an annular chamber divided into upper and lower portions and having a central pipe communicating respectively with the lower chamber and the upper chamber, the two 100

chambers being provided with valves and said supplementary chambers respectively valve seats controlling communication between the said upper and lower chambers, the upper chamber also communicating with 5 a supplemental chamber having an outlet and the lower chamber communicating with a supplemental chamber having an inlet, permitting exit of gas from the container and admittance of gas thereto. In testimony whereof we have hereunto set our hands.

MARTINUS ADRIANUS MEIJER.
RICHARD vom FELD.
